UNITED STATES PATENT OFFICE.

SEARCY T. HUTCHINSON, OF SAN ANTONIO, TEXAS.

TOY TORPEDO-EXPLoder.

SPECIFICATION forming part of Letters Patent No. 775,974, dated November 29, 1904.

Application filed September 2, 1903. Serial No. 171,650. (No model.)

To all whom it may concern:

Be it known that I, SEARCY T. HUTCHINSON, a citizen of the United States, residing at San Antonio, in the county of Bexar and State of Texas, have invented a new and useful Toy Torpedo-Exploder, of which the following is a specification.

My invention relates to toy torpedo-exploders, and has for its objects to produce a device of this character of simple construction which will be efficient in operation and one in which the torpedo will be positively exploded through the relative movement of the body and hammer and this wholly through the momentum or gravity of the body when the device is thrown from the operator, thus entirely dispensing with the employment of springs or analogous operating mechanism, with a consequent reduction in the cost of manufacture and liability of the parts becoming disarranged or defective in use.

To these ends the invention comprises the novel details of construction and combination of parts more fully hereinafter described.

25 In the accompanying drawings, Figure 1 is a side elevation of my improved device. Fig. 2 is a section centrally through the same. Fig. 3 is a similar view showing the parts in firing position.

30 Referring to the drawings, 1 indicates the body of the device composed of any suitable material, but preferably of metal, and in the form of a ball or sphere. This body has formed therethrough a main central opening 2 and a secondary lateral opening 3, disposed at right angles to the opening 2 and communicating therewith, the main opening being enlarged adjacent to its normally lower end, thus producing an upper seat or anvil 4, which 40 is accessible through the opening 3 and is designed to receive and sustain the caps or torpedoes which are to be exploded.

45 5 is a hammer or member which preferably extends through and is slidably disposed within the opening 2 and is provided adjacent to its normally lower end with a laterally-extended portion or striker 6, which during the operation of the device, as hereinafter explained, retreats into the enlarged portion of 50 opening 2 and acts upon the anvil 4 for ex-

ploding the torpedo. The normally upper end of the hammer or member 5 is perforated to permit the attachment thereto of a connecting or operating member 7, preferably in the form of a suitable length of cord, which 55 is provided at its free end with a ring or other handpiece 8 for engagement with the hand of the operator.

In practice the member 5 will be shoved downward through the body 1 to the position 60 shown in Fig. 2, in which position it will be maintained by the cord 7 at its point of attachment with the member, entering the mouth of the opening 2 and frictionally binding the hammer member therein. A cap is then inserted through the opening 3 and placed in 65 position upon the anvil 4. The operator, having previously engaged the handpiece 8, throws the ball or exploder from him, and when the device reaches the limit of its movement, determined by the length of the cord, the hammer will be moved forcibly through the body, owing to the momentum or gravity of the latter carrying it onward and brought into contact with the cap upon the anvil 4, 70 thus exploding the same.

75 From the foregoing it will be seen that I produce a device of simple construction which will be efficient in operation and in which a spring or other mechanism liable of becoming 80 disarranged or defective in practice is entirely dispensed with, while at the same time the cost of the device is reduced to a minimum. In attaining these ends it is to be understood that I do not limit myself to the precise details 85 herein set forth, inasmuch as minor mechanical changes may be made therein without departing from the spirit of the invention.

Having thus described my invention, what I claim is--

90 In a device of the class described, the combination with a body adapted to be impelled through the air and having a main opening provided with an enlarged portion, of an anvil formed within the body adjacent to the normally upper end of the enlarged portion of the opening, said body also having a secondary lateral opening communicating with the main opening adjacent to the anvil, a member or hammer disposed for reciprocation within the 95 100

main opening, said member being extended at its upper end beyond the body and having a lateral extension or striker lying within the enlarged portion of the opening beneath and 5 adapted to act upon the anvil, a flexible operating element connected with the upper extended end of the member, said body being adapted, when the motion of the device through the air is checked, to travel forward 10 upon the member and to thereby bring the striker into forcible contact with the anvil for

exploding a torpedo, and means for temporarily locking the body and member relatively to maintain the striker remote from the anvil until the motion of the device is checked. 15

In testimony that I claim the foregoing as my own I have hereto affixed my signature in the presence of two witnesses.

SEARCY T. HUTCHINSON.
